(57) **CLAIM**

The ornamental design for an absorbent sleeve, as shown and described.

DESCRIPTION

FIG. 1 is a perspective view of the absorbent sleeve,
FIG. 2 is a front view of the absorbent sleeve,
FIG. 3 is a rear view of the absorbent sleeve,
FIG. 4 is a left side view with a right side mirror image of
the absorbent sleeve,

FIG. 5 is a top view of the absorbent sleeve; and,

FIG. 6 is a bottom view of the absorbent sleeve.

The broken lines are for illustrative purposes only and form no part of the claimed design.
